UNITED STATES PATENT OFFICE

CHARLES A. DOMLER, OF PROVIDENCE, RHODE ISLAND, ASSIGNOR TO THE HADLEY COMPANY, INC., OF PROVIDENCE, RHODE ISLAND, A CORPORATION OF RHODE ISLAND

BRACELET FOR WATCHES OR THE LIKE

Application filed July 30, 1929. Serial No. 332,116.

This invention relates to articles of jewelry such as bracelets or bracelet watches, and has for its principal object the provision of a watch case or the like having a channel therethrough receiving a slidable portion of an extensible bracelet. Another object is to provide a watch case having a substantially continuous, flexible bracelet so associated with the case that the effective length of the bracelet may be increased or decreased without disconnecting the bracelet attachments. Further objects reside in the improved features of the watch bracelet hereinafter described, as pointed out in the appended claims.

A recommended embodiment of the invention is illustrated in the accompanying drawings, in which:

Fig. 1 is a front view of the improved bracelet watch;

Fig. 2 is a side view thereof;

Fig. 3 is a view similar to Fig. 2, with the watch case open and certain parts shown in section;

Fig. 4 is a plan view of a detached back section of the watch case;

Fig. 5 is a transverse section taken on line 5-5 of Fig. 4; and

Fig. 6 is a detail view illustrating an optional locking member for the bracelet.

The watch case chosen for the purpose of illustration comprises front and back sections 7 and 8 respectively, pivoted at 9 to swing from open to closed position, the sections having telescoping side flanges 11 and 12 provided with snap fastenings, such as complementary detents 13 and recesses 14, to lock the parts together. The watch movement may be mounted within the front section 7 in any usual manner, and the watch case may obviously be fashioned in any desired size or shape.

A bridge member 15 is preferably fixed along the inner face of the back 8, as by soldering or otherwise, to provide an elongate channel 16 for receiving a slidable portion of the watch bracelet, the channel preferably extending from end to end of the watch parallel to the back section 8. A crossbar 17 preferably is supported upon the

bridge member 15 at the free end of the back to furnish a constricted opening through which one end of the bracelet may be inserted and anchored.

The bracelet 18 may be a ribbon, strap or metal mesh band, or may be made of any other suitable flexible material. One end of the bracelet preferably is inserted beneath the bar 17 and attached to the watch by an anchoring member which may be detachable if desired. The anchoring member shown is a detachable one, consisting of a coiled wire 19 which is threaded into the end of the mesh bracelet shown in the drawings. The anchoring member is larger in cross section than the constricted opening through which the bracelet end is inserted, thereby to retain said end behind said opening. The bracelet is doubled upon itself adjacent said attached end to form a loop 20, then extends through the channel 16, and has its opposite end adjustably connected to the loop 20, as by a connector 21, so that the effective length of the bracelet may be adjusted by sliding the bracelet through the connector 21 and the channel 16 to vary the length of the looped portion 20.

Thus the bracelet may be extended by shortening the loop 20 when the article is to be applied over the hand, and may be tightened upon the wrist of the wearer by lengthening said loop. The tension of the tightened bracelet may in many cases be sufficient to hold it against accidental loosening, but means may be provided to prevent casual extension of the bracelet, if desired. For example, the watch case may be provided at one end with a bar 22 normally offset above one end of the channel and extending beneath the bracelet to form a bend in the bracelet and provide frictional resistance to free sliding movement of the bracelet; or a slider 23 having a locking lever 24 of usual construction may surround the looped portion of the bracelet, as indicated in Fig. 6, to secure the bracelet in its adjusted position.

By the arrangement above described, the improved bracelet watch may readily be applied to the wrist of the wearer and adjusted in position by varying the length of the brace-

let loop without disconnecting the bracelet. Accordingly, no snap fastenings or other catches, which are likely to be accidentally released or to become inoperative during use, 5 are necessary for connecting individual bracelet sections as in the bracelets heretofore provided. The channel through which the bracelet slides may be formed in the watch case itself, as illustrated, or may be 10 part of an attachment applied to the back of the watch. Obviously, the improved bracelet may be employed in association with cases or bracelet members of other useful or ornamental articles of jewelry; and the structural 15 details of the apparatus herein described may be varied to suit particular purposes without departing from the essence of this invention as defined in the appended claims.

I claim:

- 20 1. An article of the class described comprising a case having front and back sections, a bridge member within the back section and extending approximately from one side to the other of said section to furnish an elongate, open-ended channel, and a bracelet 25 slidable lengthwise through the channel, one end of the bracelet being attached to the case and the opposite end thereof being adjustably connected to a looped portion of the 30 bracelet, so that the effective length of the bracelet may be adjusted by varying the length of its looped portion. 35 2. An article of the class described comprising a watch case having front and back sections, a bridge member within the back section and extending approximately from one side to the other of said section to furnish an elongate, open-ended channel, and a bracelet 40 slidable lengthwise through the channel, one end of the bracelet being attached to the case and the opposite end thereof being slidably connected to a looped portion of the bracelet, so that the effective length of the bracelet may be adjusted by 45 varying the length of its looped portion, and means carried by the case adjacent one end of the channel for frictionally resisting movement of the bracelet through the channel. 50 3. An article of the class described comprising a case having a channel therethrough approximately parallel to its back, and a substantially continuous flexible bracelet having an extensible looped portion and a 55 portion slidable through said channel, one end of the bracelet being attached to the case and the opposite end being slidably connected to said looped portion, whereby the effective length of the bracelet may be adjusted by sliding it through said channel to 60 vary the length of its looped portion, without disconnecting the bracelet. 65 4. An article of the class described comprising a case having a channel therethrough, and a substantially continuous flex-

ible bracelet having a connector at one end, the opposite end portion of the bracelet extending through said channel and through said connector and being attached to the case to provide an extensible loop, the bracelet being slidable through the channel and connector so that its effective length may be adjusted by varying the length of its loop. 70

Signed by me at Providence, Rhode Island, this 25th day of July, 1929.
